(57) **CLAIM**

The ornamental design for a pipe for electronic cigarette, as shown and described.

DESCRIPTION

FIG. 1 is a front elevational view of a pipe for electronic cigarette showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a perspective view thereof.

The left side view is symmetrical to the right side view.
